UNITED STATES PATENT OFFICE.

ORED OLSSON, OF ORD, NEBRASKA.

WINDMILL.

Application filed November 18, 1922. Serial No. 601,719.

To all whom it may concern:

Be it known that I, ORED OLSSON, a citizen of the United States, and a resident of Ord, in the county of Valley and State 5 of Nebraska, have invented a new and Improved Windmill, of which the following is a full, clear, and exact description.

This invention has relation to windmills and has particular reference to certain improvements upon devices of a similar nature disclosed in United States Letters Patent 10 Nos. 626,559 and 1,360,013, granted respectively on June 6, 1889, and November 23, 1920.

15 The present invention has to do particularly with the improved construction and mounting of the governor which operates to automatically control the feathering of the blades; the governor bracing and supporting elements, and the automatic governor controlling device.

One of the principal objects of the invention resides in the provision of a windmill equipped with automatic means for controlling the feathering of the blades whereby to compensate for variations in the velocity of the wind and prevent racing of the mill in order that the same will be driven at a substantially uniform speed.

30 As a further object the invention contemplates an improved governor supporting and bracing construction which is extremely strong and durable, but which is very light in weight.

35 The invention furthermore contemplates an automatic governor controlling device which operates to increase the resistance as the blades are feathered whereby to prevent the throwing of the mill out of operation 40 by a sudden or temporary blast of wind of very high velocity whereby to relieve the driving mechanism of unnecessary strains caused by intermittent starting and stopping.

45 With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a perspective view of a windmill constructed in accordance with the invention and illustrating the blades disposed at a normal pitch for a wind of average 60 velocity.

Fig. 2 is a similar view illustrating the blades when feathered under the action of a wind of high velocity.

Fig. 3 is a fragmentary plan view with the 65 blades removed and illustrating the governor control.

Fig. 4 is a fragmentary sectional view taken approximately on the line 4—4 of Fig. 3.

Fig. 5 is a fragmentary transverse sectional view taken approximately on the line 5—5 of Fig. 3.

Fig. 6 is a transverse sectional view taken approximately on the line 6—6 of Fig. 3. 75

Fig. 7 is an enlarged detail side elevation of the automatic governor controlling device in its normal position when the mill is operating in a moderate wind.

Fig. 8 is a similar view illustrating the 80 position of the automatic governor controlling device when the mill is operating under the influence of a strong wind, thus effecting a sufficient feathering of the blades to reduce the speed without actually stopping the mill. 85

Fig. 9 is a similar view to Fig. 7 illustrating the initial movement of the governor controlling device when the same is manipulated by hand.

Fig. 10 is a similar view illustrating the 90 position of the governor controlling device when the mill has been thrown completely out of operation by hand.

Referring to the drawings by characters of reference 10 designates the framework of 95 the mill provided at its upper end with a housing 11 which in turn is formed with a tubular bearing 12 extending therethrough and projecting therefrom. The housing 11 and its bearing 12 may be swivelly supported from the framework 10 if desired and provided with suitable means such as a vane for normally facing the mill into the wind, not illustrated for the reason that such features form no part of the invention and 100 are common to practically all windmills. A drive shaft 13 extends through the tubular bearing 12 which bearing is provided adjacent the outer end with an anti-friction or roller bearing 14. The inner end of the 110

drive shaft has secured thereto a pinion 15 which is designed to cooperate with suitable mechanism attached to the pump rod. The outer end of the drive shaft extends beyond 5 the tubular bearing 12 and has secured thereto, for turning movement therewith, the hub 16 of the wheel or propeller which includes the spokes 17 disposed radially therefrom and the sails or blades 18 mounted for turning 10 movement on the spokes. The blades are connected to each other for simultaneous turning movement by connecting rods 19. The hub 16 is further provided with diametrically disposed oppositely offset arms 15 20 which constitute bearing arms for the governor levers 21 pivoted to the extremities of the bearing arms as at 22. The governor levers are in turn linked by the rods 23 to the blades or sails as at 24 whereby outward 20 or inward swinging movement of the governor levers will effect respectively a turning of the blades or sails 18 on the spokes to vary the pitch of the blades. Weights 25 are mounted for longitudinal sliding adjustments 25 on the governor levers 21 and said weights are retained in their adjusted positions by set screws 26. In order to steady and brace the outer ends of the spokes and retain the same in fixed relation to each 30 other, connecting rods 27 are provided. In order to steady, brace and support the outer extremities of the governor levers while at the same time admit of their swinging movement, a rod 28 is attached as at 29 to the outer end of each governor lever, said rod being swingingly connected as at 30 with a bearing member 31, which bearing member is held in relatively fixed relation to the spokes by three brace rods 32 to the outer 40 ends of which the member 31 is connected, while the inner ends thereof are connected respectively to the rods 27 and the spokes. The governor levers which operate by centrifugal force are normally retained in their 45 normal inactive position by a spring 33 which is interposed between the head 34 at the extreme forward end of the drive shaft and a sliding sleeve 35 mounted on the drive shaft between the outer end of the same and 50 the hub 16. The sliding sleeve 35 is connected by links 36 to the inner extremities 37 of the governor levers. A second spring 38 is interposed between the sliding sleeve 35 and the hub 16 to assist in absorbing the shock 55 upon the return of the governor levers to normal position after outward swinging movement.

In order to provide automatic means for 60 retarding or restraining the action of the governor and prevent a complete feathering of the blades due to sudden drafts of increased velocity and short duration, a second sliding sleeve 39 is provided. The sleeve 39 is mounted on a tubular bearing 65 and is axially movable thereon between the

shoulder 40 formed by the enlarged end of the tubular bearing which houses the anti-friction or roller bearing 14 and the shoulders 41. The sliding sleeve 39 is connected by links 42 to the inner extremities 70 37 of the governor levers, said links being connected to a ring or annulus 43 which is rotatable in the annular groove 44 on the sleeve 39. The tubular bearing 12 is provided with a longitudinal groove 45 in its 75 outer periphery within which a rod 46 is slidable, said rod being connected to the sleeve 39 and serving to prevent rotation of the sleeve. The rod 46 extends through the housing 11 and is connected to one arm 47 of a bell crank lever 48 which is fulcrumed as at 49 to a bracket 50 extending rearwardly from the housing 11. The opposite arm 51 of the bell crank has pivoted to its free end as at 52 a leg 53 and the free extremity 80 of said leg is provided with laterally disposed aligned bearing ears 54 in which a shaft 55 is mounted for longitudinal movement. The shaft is provided with a semi-spherical head 56 at its lower extremity 90 which is adapted to bear against the lug 50a of the bracket 50. A coiled expansion spring 58 is interposed between the head 56 and the lowermost bearing ear to normally effect relative separation between the head 95 and the leg 53, said separating movement being arrested by a stop pin 59 which engages with the uppermost bearing ear. The upper pivoted end of the leg 53 is provided with right angularly disposed extensions 100 60 and 61, the former having swivelly connected thereto a rod 62 which passes through a bearing lug 63 secured to the arm 51 of the bell crank lever. The outer free end of the rod is provided with a stop nut 64 and equalizing springs 65 and 66 encircle the rod 62 and are interposed respectively 105 between the connected end of the rod and the bearing lug and the stop nut 64 and the opposite side of the bearing lug. The 110 angularly disposed extension 61 has connected thereto a depending rod 67 by means of which manual feathering of the blades may be accomplished by a person on the ground at the base of the frame structure 115 10. The arm 51 of the bell crank is provided with a stop shoulder 68 which constitutes a positive stop with which the leg 53 initially engages when a downward pull is exerted on the rod 67. The spokes and sails or blades are braced by angularly disposed brace spokes 69 which connect respectively with the spokes 17 and the head 34 of the drive shaft and a rotary hub member 70 which is mounted between the shoulders 41 on the tubular bearing 12.

In use and operation, the spring 33 when the mill is operating under a wind of average velocity, operates to throw the weighted governor levers toward the axial 130

center of rotation of the propeller or wheel whereby the blades are disposed at a proper pitch to obtain a maximum force from the wind. Where the velocity of the wind increases above the average to such an extent that the mill would race, the weighted governor levers will be swung by centrifugal force against the action of the spring 33 due to the connection of the same by the rods 23 with the blades or sails 18, the blades will be feathered or turned to increase their pitch and reduce the surface presented to the wind to slow the action of the mill. When blasts of wind of high velocity and short duration occur, the automatic governor controlling device is brought into play to constitute an auxiliary means for preventing the complete feathering of the blades and stopping of the mill. The operation is as follows: The outward swinging of the governor levers 21 due to the increased speed of the mill will initially operate against the spring 33 thus drawing forward on the links 42 which are connected to the sliding sleeve 39. The initial forward movement of the sliding sleeve 39 exerts a pull on the rod 46 thus swinging the bell crank 48 until the head 56 engages with the bracket lug 50^a. At this point the auxiliary spring 58 will be brought into play to increase the resistance of the swinging movement of the governor levers 21. If the wind is of a short duration, the spring will sufficiently retard the complete feathering of the blades to preclude the absolute stopping of the mill. If, however, the wind is of long duration, the spring will be gradually compressed as illustrated in Fig. 8 but the blades cannot be feathered enough to bring the mill to a full stop. When the velocity of the wind decreases and the governor arms swing back to normal position, the spring 38 will function to cushion and absorb the shock of the return of the blades to their normal pitch. In event it is desired to manually throw the mill out of operation, the operator grasps the rod 67 and pulls downwardly thereon, the downward pull on the rod 67 initially effecting a swinging movement of the leg 53 against the stop shoulders 68 at which point the head 56 will be disposed in such a position as to clear the bracket lug 50^a when a further downward pull is exerted on the rod 67. When a further pull is exerted downward on said rod 67 the bell crank will be swung on its pivotal point 49 to throw the arm 47 thereof forwardly, thereby effecting a forward shifting of the sliding rod 46 and a forward sliding movement of the sleeve 39 which in turn will throw the governor levers 21 outwardly to completely feather the blades and stop the mill. The initial swinging of the leg 53 against the stop shoulder 68 causes a compression of the spring 66,

which spring will function, when the rod 67 is released to return the leg 53 to its normal position as illustrated in Fig. 7.

I claim:

1. The combination with a windmill, of 70 governor arms controlling the angular disposition of the blades of the wind wheel, a link longitudinally movable by said governor arms, a bell crank lever connected at one end to said link, a leg on said bell 75 crank lever adapted to engage the windmill frame, and means carried by said leg for yieldably limiting the operating movement of the governor whereby to provide a supplemental retarding action to the swinging 80 of the blades.

2. In a windmill comprising a rotary drive shaft, a wheel including a hub secured to the drive shaft for rotation therewith, spokes radiating from the hub and blades or sails mounted on the spokes for turning movement, a centrifugal speed governor including governor arms pivoted to the hub for rotation therewith, a swinging brace connected respectively with the spokes and the free outer ends of the governor levers, and a connection between the governor arms and the blades for controlling the turning movement of the same to vary 90 the pitch of the blades. 95

3. The combination with a windmill, of 100 governor arms for controlling the angular disposition of the blades of the wind wheel, a bell crank and operative connection between one arm of the bell crank and the governor arms, a leg swingingly carried by the free end of the other arm of the bell crank, a spring pressed foot normally projecting from the free end of the leg, means for maintaining the leg in a predetermined normal relation to the bell crank, a lug on the windmill frame disposed in the normal path of movement of the foot and engageable thereby to yieldably limit and retard the movement of the bell crank, the governor arms and turning of the blades, and manually operable means connected with the leg adapted upon initial manipulation to swing the leg whereby to dispose the foot in a position to escape the lug upon further manipulation of said manually operable means. 110

4. The combination with a windmill, of 120 governor arms for controlling the angular disposition of the blades of the wind wheel, a bell crank and operative connection between one arm of the bell crank and the governor arms, a leg swingingly carried by the free end of the other arm of the bell crank, a spring pressed foot normally projecting from the free end of the leg, means for maintaining the leg in a predetermined normal relation to the bell crank, said means consisting of an apertured bearing element on the latter bell crank arm, an apertured extension on the leg, a rod extending 125 130

4

through said apertured elements, abutments at the opposite ends of the rod and coiled expansion springs surrounding the rod and interposed respectively between the bearing 5 element and the extension and between the bearing element and the abutment, a lug on the windmill frame disposed in the normal path of movement of the foot and engageable thereby to yieldably limit and retard 10 the movement of the bell crank, the governor arms and turning of the blades, and manually operable means connected with the leg adapted upon initial manipulation to swing the leg whereby to dispose the foot in a position 15 to escape the lug upon further manipulation of said manually operable means.

5. The combination with a windmill including a centrifugal governor for controlling the angular disposition of the blades 20 of the wind wheel, of means for automatically controlling the governor and for manually feathering the blades to stop the wheel, comprising a bell crank, a connection between one arm of the bell crank and the 25 governor, a leg pivoted to the free end of the other arm of the bell crank, a foot carried by the free end of the leg, means for normally projecting the foot beyond the free end of the leg, a lug on the windmill frame, 30 means for normally maintaining the foot in a position to engage the lug upon movement of the bell crank by the governor, and manipulating means connected with the leg

and adapted upon initial manipulation to swing said leg relative to the bell crank 35 whereby to throw the leg to a position in which the foot will miss the lug and whereby upon further manipulation of said means the bell crank is capable of movement to allow for the full feathering of the blades to 40 stop the wheel.

6. The combination with a windmill including a centrifugal governor for controlling the angular disposition of the blades of the wind wheel, of means for automatically controlling the governor and for manually feathering the blades to stop the wheel, comprising a bell crank, a connection between one arm of the bell crank and the 45 governor, a leg pivoted to the free end of the other arm of the bell crank, a foot carried by the free end of the leg, means for normally projecting the foot beyond the free end of the leg, means for maintaining the free end of the leg in a predetermined relation to the bell crank, a lug on the windmill frame disposed in the normal path of movement of the foot, and manually operable means connected with the leg adapted upon initial manipulation, to swing the foot to a 50 position whereby upon further movement thereof the foot will miss the lug, to allow for a full feathering of the blades and stopping of the mill.

ORED OLSSON.
